UNITED STATES PATENT OFFICE.

JOHN P. WARNER, OF WASHINGTON, DISTRICT OF COLUMBIA, ASSIGNOR TO
A. F. NAVARRE, OF SAME PLACE.

HEATER AND PURIFIER FOR FEED-WATER.

SPECIFICATION forming part of Letters Patent No. 480,584, dated August 9, 1892.

Application filed November 14, 1891. Serial No. 411,891. (No model.)

To all whom it may concern:

Be it known that I, JOHN P. WARNER, a citizen of the United States, residing at Washington, in the District of Columbia, have invented certain new and useful Improvements in Heaters and Purifiers for Feed-Water; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in that class of feed-water heaters and purifiers in which the water is not only heated, but also purified of all impurities and deleterious matters by the action of exhaust and live steam.

20 The object of the invention is to simplify such feed-water heaters and purifiers in such manner that the number of pieces usually required in the construction of those now in use is reduced to a minimum; also, that by removing a single cover the entire interior of the body of the heater is exposed to view for inspection or repair; furthermore, to produce a very effective and economical feed-water heater and purifier at a very moderate expense and one not liable to get out of order.

25

The invention consists in the construction of certain details and arrangement of parts, as will be more fully described hereinafter, and specifically pointed out in the claims, reference being had to the accompanying drawings, and the letters of reference marked thereon.

Like letters indicate similar parts in the different figures of the drawings, in which—

Figure 1 represents a vertical section of the 40 feed-water heater and purifier. Fig. 2 is a cross-section of the same on line xx of Fig. 1.

In the accompanying drawings, A is the main body or shell, made of any suitable size and any material desired—such as cast-iron, 45 composition, malleable iron, &c.—and made of such strength as to resist considerable pressure. This body is provided with an inward-projecting flange a , preferably, although it may be an annular outer flange, if desired, and project around the side. To this

flange the cover B is tightly bolted, having suitable packing placed between it. The bolts b are shown at the upper and lower ends, and the bolt-holes are indicated by the dotted circles in Fig. 1.

55

The interior of the body A, which is preferably of rectangular form, with a semicircular top, is provided with a partition C, extending from side to side, and between it and the outer shell exhaust-steam is admitted through the inlet-opening d , and passing to the other side of said partition it passes through the outlet-opening e to a condenser or any other desired place. A petcock f and g enters the space between said partition, and thus the 60 condense water can be withdrawn. Another corrugated or similar-shaped partition D is arranged in the space formed by the partition C and forms the central space or receptacle E, into which live steam is conveyed 65 through the pipe F, that is connected to the boiler or other source of supply. A check-valve h is placed in the pipe F to prevent the steam returning. At the upper end of the pipe F is arranged a branch pipe G, which is 70 provided with a stop-valve i , and terminating in a T-piece k , containing a number of perforations and forming steam-jets. The water is admitted through the pipe H into the space 75 formed between the inside of the partition C and the outside of the corrugated partition D, thus receiving the heat of the steam from 80 both sides in passing up the space and over the top of the other side. In passing over the top the water meets the live-steam jets from 85 the T-piece k and is heated to a still higher degree of temperature. It finally escapes through the outlet-opening l in a highly heated and purified condition, as all impurities contained in the water are precipitated and pass 90 into the mud-drum I, from which they can be blown out whenever found necessary or desirable.

If desired, relief-valves may be arranged 95 wherever required to permit the escape of any excessive pressure of steam. The blow-off pipe is provided with a suitable stop-valve m , to be opened whenever it is necessary to blow out the impurities, &c. A shield n may be provided over the outlet-opening l to pre- 100

vent the escape of any impurities. The inlet-pipe H for the water is also provided with a suitable stop-valve h' . The partition D may be serrated or of any similar shape, if desired.

5 A steam-jet o may be arranged in the pipe H to assist in forcing the water into the heater, while at the same time heating it.

Having thus described my invention, what I claim is—

10 1. In heaters and purifiers for feed-water, the combination of the main body A, provided with the partition C and corrugated partition D, forming the space E for live steam in the center and on the outside of said partition C for exhaust-steam, with the steam and water inlet and outlet pipes and arranged substantially as set forth.

15 2. A heater and purifier for feed-water, consisting of the shell A, provided with the partition C and the corrugated partition D, in com-

bination with the steam-pipe F, having branch pipe G, having perforated T-piece k, the water-pipe H, provided with a steam-jet o, and the mud-drum I and the exhaust-pipes, all arranged as shown, and for the purpose specified. 25

3. The combination of the main body A, provided with the partition C and corrugated pipe D, constructed as shown, with the steam-pipe F, having branch pipe G and T-pipe k at the upper end and entering into the central space E at the lower end, the exhaust inlet and outlet pipe, and the water inlet and outlet pipe, all arranged as shown and specified. 30

In testimony whereof I affix my signature in presence of two witnesses.

JOHN P. WARNER.
